UNITED STATES PATENT OFFICE.

ANGEL FERNÁNDEZ, OF HABANA, CUBA.

STEAM-BOILER.

1,105,896.

Specification of Letters Patent.

Patented Aug. 4, 1914.

Application filed March 17, 1914. Serial No. 825,392.

To all whom it may concern:

Be it known that I, ANGEL FERNÁNDEZ, a citizen of the Republic of Cuba, residing at Habana, Cuba, have invented certain new and useful Improvements in Steam-Boilers, of which the following is a specification.

The present invention relates to improvements in steam boilers, particularly to internally fired boilers and the improvements consist mainly in cutting the lower part of 10 the boiler mantle away, *i. e.* that part of the same which usually comes into contact with the water forming in pools at the bottom of a ship.

15 It is the object of the present invention to prevent the bulk of the stagnant water at the bottom and the lower part of the firebox from causing changes and dilatations of the boiler which are the cause of the 20 rapid destruction of the same and of many accidents.

It is a well known fact that in order to 25 avoid the non-uniform dilatations of the upper and lower parts of internally fired boilers a forced circulation of the water within the boiler must be established as long as steam is generated by using the hydrokineter of Weir. By means of this auxiliary apparatus alone the non-uniform dilatation 30 of the boiler can be avoided as the upper layers of strata of the water will rapidly evaporate while the water near the bottom is nearly freezing. The hydrokineter by means of an auxiliary boiler which commonly 35 works under a pressure of thirty pounds per square inch, will hold the water at the bottom of the main boiler at a temperature of 130 degrees C. However modern boilers work with higher pressure and 40 therefore the hydrokineter will become inefficient while on the other hand the temperature and the dilatation of the upper $\frac{1}{2}$ and the lower part of the bottom of the boiler mantle which latter is hardly dilatating should also be taken into consideration. 45 Another cause for the non-uniform dilatation is the refrigeration of the water in the lower part of the boiler which tends to hold that part of the boiler at a lower temperature 50 than the remaining part.

The cause of the deformation or flattening of many of the cylindrical boilers now in use is only to be seen in the non-uniform dilatation of the upper and lower half cylinders, in consequence of which the boiler loses its geometrical form and takes the

form of an ellipsoid unable to withstand the high pressure which the cylindrical form was able to stand.

In the accompanying drawing: Figure 1 is a front view of a boiler partly in vertical section with three interior fire-boxes according to the present invention. Fig. 2 is a vertical longitudinal section through the same. Fig. 3 is a detail view of the connection between the handles of two adjacent fire-boxes in transversal section. Fig. 4 is an end view of a boiler with two fire-boxes according to the present invention. Fig. 5 is a similar view of a boiler with one fire-box according to the present invention.

The mantle 1 of the boiler is cut straight on its lower part so as to form in cross section about $\frac{1}{3}$ of a circle, and the mantles 2 of the fire-boxes 3 are shaped accordingly. The exterior walls 2' of the mantles 2 of the lateral fire-boxes 3 and the corresponding wall of the mantle 1 are united by means of a double row of rivets and the connection is supported by lateral posts 4 upon which said mantle rests. The side walls 2' of the mantles 2 of two adjacent fire-boxes are connected by means of a steel plate 5 forming in section an inverted horse-shoe the inclined end walls of which are secured to said walls 85 of the adjacent fire-boxes by means of rivets. The plates 5 are secured to the upper part of the boiler by means of a row of vertical rods 6 which extend through the base of the horse-shoes and the mantle 1 of the 90 boiler. Their lower ends being secured by the intermediary of shoes 7 and nuts 8 while their upper ends are secured to the boiler mantle by the intermediary of a saddle 9 and nuts 10. The rods 6 pass between the 95 vertical rows of the flues 11 of the boiler which are mounted in the front plate 12 and the vertical transversal plate 13 which limits in front the fire-box or smoke box 14 which is also limited by a wall 15 riveted to the 100 plate 13 and the rear part of which is vertical and parallel to the rear plate 16 of the boiler which is riveted to the mantle 1 and to the mantles 2 of the lateral fire-boxes 3.

The mantle 1 of the boiler and the mantles 105 2 of the fire-boxes 3 are secured to the horse-shoe pieces 5 by means of a row of horizontal transversal rods 17 which either from one side of the mantle cross the horse-shoe (Figs. 1 and 2), or which tangentially pass 110 the same as shown in Fig. 4. In the former case they extend through the mantles of

both adjacent fire-boxes and are provided at their outer ends with a thread for the reception of nuts 18 engaging shoes 19 interposed between said nuts and said walls, while the 5 outer ends of the rods 17 of the two lateral fire-boxes are screw threaded and carry nuts 20 and shoes 21 between said nuts and the outer walls of the boiler (Fig. 1 to Fig. 2).

In the construction illustrated in Fig. 4 the 10 rods 17 extend through the side plates of the boiler and are secured by nuts 20 screwed upon their outer threaded ends by the intermediary of shoes 21, while their middle parts pass the lower end of the horse-shoe 5.

15 The outer extremities of the grate bars 22 are mounted below the geometrical axis of the mantles 2 upon transversal angle irons 23 and 24 and their inner ends rest upon inverted T-beams in the center. The fire box 20 14 is closed at the bottom by a metal bridge 26 of angular cross section upon which the fire brick wall 27 is located which is so disposed that the flames and the smoke are guided upwardly; said bridge 26 also carries a fire brick floor 28. The ash pit is 25 formed with a bottom plate 29 with inclined walls and is adapted to receive water and its side walls are secured to the side walls of the mantle 1 by means of screws or the like.

30 At the front part of the head plate 12 is disposed the smoke chamber 30 for the exhaust of the smoke and fire gases through the chimney. The direction of flow of the fire gases is indicated by arrows, see Fig. 2.

35 According to the construction illustrated in Fig. 4 the boiler has two interiorly disposed fire-boxes the construction of which is entirely analogous to that of a boiler having three fire-boxes and the transversal rods 17 40 pass under the horse-shoe pieces 5, while the dotted lines indicate the same parts shown in Figs. 1 and 2 in the same positions.

In Fig. 5 a boiler is illustrated provided with a single interior fire-box, and in which 45 the horse-shoe pieces 5 and the vertical rod 6 are dispensed with and which shows only the horizontal rods 17, the upwardly inclined ends of which are secured to the similarly inclined ends of the boilers by means 50 of screws 31 and nuts 32.

I claim:

1. In boilers of the character described the combination of an exterior mantle for said boiler cut away at its lower part, fire-boxes

at said cut away part of the boiler, mantles 55 for said fire-boxes also cut away at their lower parts, and inverted horse-shoe pieces riveted to the ends of two adjacent of the intermediary fire-boxes, and means for connecting the ends of the exterior boiler mantles with the ends of the two lateral fire-boxes.

2. In a boiler of the character described the combination of an exterior mantle for said boiler having its lower fifth part cut 65 away, supports for said boiler, fire-boxes below the geometrical axis of said mantle, a mantle for each of said fire-boxes, means for securing the outer ends of said boxes to the outer ends of the mantles, and means for 70 securing the adjacent ends of two of said fire-boxes to each other, an ash pit below said fire-boxes having inclined side walls, nests of tubes within said boiler and means for supporting the vertically arranged nests of 75 said tubes secured to the outer end of the mantle securing means for two adjacent fire-boxes and to the outer face of the boiler mantle respectively.

3. In a boiler of the character described 80 the combination of an exterior mantle for said boiler having its lower fifth part cut away, supports for said boiler, fire-boxes below the geometrical axis of said mantle, a mantle for each of said boxes, means for securing the outer ends of said boiler mantle to the outer ends of the mantles of the two lateral fire-boxes, inverted horse-shoe pieces having their free ends connected with the lower ends of the mantles of two adjacent 90 fire-boxes, a horizontal rod connecting two of said mantles at the place of connection through said horse-shoe pieces and secured in position, an ash pit below said fire-boxes having inclined side walls and secured to 95 said boiler mantles, rods connecting the ends of each of the fire-boxes, and grate bars resting upon angle irons and with their inner ends upon an inverted T-beam secured to the boiler plates, 100 and rods for connecting said horse-shoe pieces with the top of the boiler mantles.

In testimony whereof I affix my signature in presence of two witnesses.

ANGEL FERNÁNDEZ.
